UNITED STATES PATENT OFFICE.

CHARLES L. GOODRUM, OF NEW YORK, N. Y., ASSIGNOR, BY MESNE ASSIGNMENTS, TO
WESTERN ELECTRIC COMPANY, INCORPORATED, A CORPORATION OF NEW YORK.

MACHINE-SWITCHING TELEPHONE-EXCHANGE SYSTEM.

1,202,281.

Specification of Letters Patent.

Patented Oct. 24, 1916.

Application filed June 28, 1915. Serial No. 36,719.

To all whom it may concern:

Be it known that I, CHARLES L. GOODRUM, a citizen of the United States, residing at New York, in the county of New York and State of New York, have invented certain new and useful Improvements in Machine-Switching Telephone-Exchange Systems, of which the following is a full, clear, concise, and exact description.

10 This invention relates to machine switching telephone exchange systems of the step-by-step type, and particularly to a system of this type wherein trunks lead from the connectors to private branch exchange switchboards.

It is customary to assign to a private branch exchange a single number just as if it were an ordinary substation, and to set the connector switch in the usual way under control of a suitable sender upon the first of such trunk lines. The connector then tests such line automatically. If the same is busy, it passes on and tests the remaining trunk lines in succession until an idle one is found, 25 whereupon it extends the call in the well-known manner. In case all the trunks are busy, a busy signal is transmitted to the calling party.

It is the object of this invention to provide a new and improved connector circuit arrangement for effectively performing these functions in a two-wire system, wherein the private branch exchange trunks are grouped upon special connectors, and wherein the 35 connectors are controlled by steering or side switches.

In the circuit arrangement of this invention, the operation of the connector is the same as those well known in the art up to the 40 point of testing the first of the private branch exchange trunks assigned to the particular number involved, that is to say, the side or steering switch in position 1 places the primary stepping magnet of the connector under control of the stepping relay in order to set the connector brushes in accordance with the tens digit of the wanted subscriber's number. Upon the termination 45 of this operation, the side switch places the secondary stepping magnet under control of the stepping relay to set the connector onto the first of the equivalent lines leading to the

private branch exchange corresponding to the number in question. If the line is idle the side switch control magnet releases the 55 side switch into the ringing position. It is from this point on that the present circuit arrangement differs from the prior art.

In accordance with the invention, the side switch escapement magnet is made slow-act- 60 ing, and during the transmission of the units digit is maintained energized by impulses from the armature and back contact of the stepping relay. Thus, when the sender re- 65 stores and maintains the line circuit closed, its armature begins to drop away. The relation between the side switch escapement mechanism and the escapement magnet armature is such, however, that it does not re- 70 lease the side switch until it reaches the end 70 of its stroke. Before it reaches the end of its stroke, it closes a circuit including its own winding, the secondary stepping mag- 75 net winding and the connector test brush. Now under the assumed condition that the 75 first line is busy and has ground upon its test terminal, the side switch escapement magnet closes a circuit for the said stepping magnet, which steps the brushes onto the next set of terminals which represents an 80 equivalent line to that just tested. In case this line is idle, its test terminal is un- 85 grounded and the escapement magnet de-energizes and releases the side switch into the ringing position. If, on the contrary, 85 this line is also busy, the escapement mag- net again attracts its armature before it has fallen back far enough to release the side switch, and near the end of its forward 90 stroke again breaks its own circuit and that 90 of the secondary stepping magnet and again de-energizes, its armature, upon closing its back contact, giving another impulse to the secondary stepping magnet. In this manner the connector is stepped ahead until an un- 95 grounded test terminal is reached, when connection is made to such line. Each group of lines leading to the same private branch exchange or to the same station, is followed 100 by a set of contacts upon which the connector brushes come to rest, if all the trunks are busy, and transmits a busy signal to the calling party in the well-known manner.

Referring to the drawings, the connector

circuit only is shown, it being understood that a connection would ordinarily lead from the calling substation A through one or more finders or equivalent switches and group selectors, and finally through the connector shown, to the private branch exchange.

Figure 1, therefore, shows only the connector circuit of this invention, and Fig. 2 is a detail view of the side switch escapement mechanism and the control magnet therefor.

The invention will be readily understood from a description of the operations involved in setting up a connection. The removal of the receiver by the calling party at substation A initiates the movement of the line finder. When such finder has connected with the calling line, the stepping relay 10 at the first selector is energized over the following circuit: free pole of battery, left winding of said relay, conductors 11, 12, brush 13, terminal 14, line conductor 15 through the telephonic apparatus at substation A, line conductor 16, terminal 17, brush 18, conductors 19 and 20, right winding of relay 10 to ground. Relay 10 thereupon closes the following circuit for slow-acting relay 21 as follows: free pole of the battery, relay 21, conductors 22 and 23, armature and back contact of relay 24, conductors 25 and 26, armature and front contact of relay 10 to ground. The slow-acting relay 21 thereupon, at its left armature and back contact, opens the circuit of release conductor 30 leading back to the line finder or line finders and prepares a circuit for slow-acting magnet 27, which is the escapement magnet of the side switch. The calling party now operates his sender 31 and interrupts the line circuit a number of times, corresponding to the tens digit of the wanted line.

Each time the armature of relay 10 closes its back contact, an impulse is sent to the primary stepping magnet 32 of the connector over the following circuit: free pole of the battery, magnet 32, side switch arm 33 and its first contact, conductor 34, 35, right armature and front contact of relay 21, conductor 29, armature and back contact of relay 10 to ground. The magnet 32 thus steps the brushes 36, 37 and 38 into operative relation to the group of terminals containing the group of trunks leading to the desired private branch exchange. Upon the first closure of the back contact of relay 10 the slow escapement magnet was energized over the following path: free pole of battery, left winding of magnet 27, conductors 28, 35, right armature and front contact of relay 21, conductor 29 to ground. When the sender 31 completely restores and maintains the line circuit closed, the circuit traced for the escapement magnet 27 is

opened at the armature and back contact of stepping relay 10, and after an interval the magnet 27 allows its armatures to retract, whereupon the side switch is released into the second position in the well-known manner. The subscriber now again operates his dial 13 interrupting the line circuit a number of times, corresponding to the units digit of the wanted number. Each time the relay 10 closes its back contact, the following circuit is closed for the secondary stepping magnet 39; free pole of the battery, magnet 39, side switch arm 33 and its second contact, conductors 34 and 35, right armature and front contact of relay 21, conductor 29, armature and back contact of relay 10, to ground. The magnet 39 thereupon steps the brushes in a secondary direction over the terminals of the selected group. The first retraction of the armature of relay 10 again closed a circuit for the side switch escapement magnet 27 over the circuit previously traced. When the sender completely restores and maintains the line circuit closed, the maintained attraction of the armature of relay 10 opens the circuit of slow-acting escapement magnet 27. Assuming now that the first of the private branch exchange trunks, whose terminals are indicated by the numbers 40, 41, 42 is busy, the multiple test terminals 42 thereof will be grounded. Thus, remembering that the side switch is now in the second position, the armature of the slow-acting escapement magnet 27, at the beginning of its retractive movement, closes the following circuit for the secondary stepping magnet 39 to step the brushes 36, 37, 38 on to the next trunk, which is an equivalent line leading to the same private branch exchange: free pole of the battery, magnet 39, side switch arm 33 and its second contact, conductors 34, 28, armature and back contact of escapement magnet 27, conductor 43, side switch arm 44 and its second contact, conductor 45, test brush 38 to grounded test terminal 42. Simultaneously with the closure of this circuit through the secondary stepping magnet 39, a circuit is closed in parallel therewith for the side switch escapement magnet 27. This circuit is as follows: free pole of battery, left winding of magnet 27, armature and back contact of magnet 27, conductor 43, side switch arm 44 and its second contact, conductor 45, test brush 38 to said grounded test terminal. Thus, the magnet 27 again attracts its armature before it has moved a sufficient distance to release the side switch into the ringing position. This will be clear from a consideration of Fig. 2. This figure shows the side switch magnet 27 energized and the side switch in its second position. This is the condition that prevails just as the sender 31 restores and maintains the circuit of 130

stepping relay 10 closed. It will be noted that the pin 56 on the armature 52 of the escapement magnet 27, maintains open the connection between springs 50 and 51, which correspond to the armature 57 and back contact 58 of the magnet 27 in Fig. 1. This armature 52 is pivoted at 59 upon the same axis as that of the arm 60 to which the toothed U-shaped spring 70 of the escapement mechanism of the side switch is pivoted. The end of the armature 52 can move a relatively great amount in its retractive movement before striking the projection 53 on the arm 60, and release the arm 83 from engagement with the second tooth 61 of the upper member 55 of spring 70 to permit the spring 62 to come into play to move the side switch arms 71 onto the third set of contacts 72, that is to say, with the arm 83 in engagement with the third tooth 63 of the lower member 64.

Referring back to Fig. 1, it will be apparent therefore that as long as the test brush 38 encounters grounded test contacts 42, which represent busy lines, impulses will be sent to the secondary stepping magnet 39. When, however, the test brush encounters a test contact 42 from which ground is removed, which indicates that the line represented thereby is idle, there is no circuit for the side switch magnet 27, and it allows its armature to retract to its extreme position, thus releasing the side switch into the third position. Side switch arm 44 in this position grounds the multiples 42 of the seized trunk to cause this line to test busy to other connectors. In position 3, the generator is connected in circuit with the seized trunk in the well-known manner. Since this forms no part of the present invention, the bell at the private branch exchange is not shown. It will be understood that the operator will respond to the ringing of the bell or the lighting of a lamp, as the case may be, and by depressing a key or inserting a plug in a jack, bring her head set 65 in circuit to respond to the calling party and determine his wants. Upon the insertion of such head set into the circuit, the relay 24 which is marginal, at its armature and back contact opens the short-circuit about the right-hand winding of the side switch escapement magnet 27, whereupon the side switch becomes energized. This circuit is as follows: free pole of battery, relay 21, conductors 22, 74, 75, 26, armature and front contact of stepping relay 10 to ground. The side switch is released into the fourth position by the energization of the magnet 27 at this time, since the tooth which ordinarily stops the arm 83 is removed from the upper member 55, and the arm 83 therefore is not stopped until it reaches the tooth 76, at which time the side switch arms 71 are in contact with the fourth set of terminals. Current is fed

to the called party over the windings of the called supervisory relay 65 in the well-known manner.

When the calling and called parties hang up their receivers the release magnet 49 is energized over the following circuit: free pole of the battery, release magnet 49, conductor 66, primary off-normal spring PON (now closed), right armature and back contact of relay 65, conductor 82, left armature 75 and back contact of relay 21, conductor 80, conductor 67, left armature and back contact of relay 65, conductor 68, right armature and back contact of relay 21, conductor 29, left armature and back contact of relay 80 to ground. The release magnet 49 thereupon restores the connector and side switch. When the connector is completely restored it opens off-normal contact PON, thus de-energizing magnet 49. The closure of the 85 armature of relay 10 to its back contact grounds conductor 78, leading back to the group selectors and finders or equivalent switches, to release the same in the well-known manner.

Each group of terminals, representing a group of trunks leading to the same substation or to the same private branch exchange operator's switchboard, as the case may be, is followed by a set of contacts 79, 80, 81. 95 Contact 81 has a busy tone thereon. The connector brushes will always come to rest upon this set of terminals if all the trunks are busy, and give a busy signal to the calling party.

What is claimed is:

1. In a telephone system, the combination with a plurality of lines, an automatic switch wherein said lines terminate in groups and having a test terminal for each line and a test wiper, means for grounding test contacts of busy lines, a side switch, a spring adapted to advance the same, of a slow-acting control magnet for said side switch constructed and arranged to allow 105 said spring to advance said side switch only after its armature has retracted a predetermined distance, a stepping magnet, a sender for operating the same to set said test wiper on the first one of a group of said test terminals, and circuits including grounded test terminals of busy lines, said test wiper, and said control and stepping magnets, and leading through an armature and back contact of said control magnet and closed after said 115 armature has retracted a predetermined distance less than that necessary to release the side switch.

2. In a telephone system, the combination with a plurality of groups of lines, each 125 group running to the same substation, an automatic switch wherein said groups terminate and having a test terminal for each line and a test wiper, means for grounding test contacts of busy lines, a side switch, a spring 130

- adapted to advance the same, of a slow-acting control magnet for said side switch constructed and arranged to allow said spring to advance said side switch only after its armature has retracted a predetermined distance, a stepping magnet, a sender for operating the same to set said test wiper on the first one of a group of said test terminals, and circuits including grounded test terminals of busy lines, said test wiper, and said control and stepping magnets, and leading through an armature and back contact of said control magnet and closed after said armature has retracted a predetermined distance less than that necessary to release the steering switch.
3. In a telephone exchange system, the combination with a plurality of groups of lines, each group running to the same substation, an automatic switch wherein said groups terminate and having a test terminal for each line and a test wiper, means for giving said wiper a movement in a primary direction under control of said sender, a stepping magnet for moving said wiper in a secondary direction under control of said sender and into engagement with the first line of the desired group, means for grounding test contacts of busy lines, a side switch, a spring adapted to advance the same of a slow-acting control magnet for said side switch constructed and arranged to allow said spring to advance said side switch only after its armature has retracted a predetermined distance, and circuits including grounded test terminals of busy lines, said test wiper, and said control and stepping magnets, and leading through an armature and back contact of said control magnet and closed after said armature has retracted a predetermined distance less than that necessary to release the side switch.
4. In a telephone system, the combination with an automatic selector having fixed and movable terminals including test terminals and a motor magnet, of a side switch for controlling the selector and being provided with a magnet and a contact closed as said magnet is deenergized, and a circuit for the selector motor magnet including test terminals of said selector and said contact of the side switch magnet.
5. In a telephone exchange system, the combination with a plurality of lines, an automatic switch wherein said lines terminate in groups and having a test terminal for each line, and a test wiper, means for changing the electrical condition of the test terminals of busy lines, a steering switch, means tending to advance the same, a control magnet for said steering switch adapted to allow said means to advance the same only after its armature has retracted a predetermined distance, a stepping magnet for said automatic switch, means for setting said test wiper on the first of a group of test terminals, and circuits including test terminals of busy lines, said wiper and said control and stepping magnets, and including an armature and back contact of said control magnet and closed when said armature has retracted a predetermined distance less than that necessary to release the steering switch.

In witness whereof, I hereunto subscribe my name this 25th day of June, A. D. 1915.

CHARLES L. GOODRUM.
